SLINGSHOT GUN

James R. Keadle, Alderson, W. Va.

Application July 23, 1951, Serial No. 238,076

5 Claims. (Cl. 124—20)

1

This invention relates to toy guns of the type having means for shooting a projectile, and in particular a gun in the form of a pistol or rifle having an elastic band mounted on the outer end of a barrel and adapted to be held between jaws of a slider wherein with the jaws actuated by a trigger the band is released for discharging a projectile.

Various types of toy guns have been provided with rubber bands, springs, and the like for shooting darts, arrows, and other projectiles, however, it has been found difficult to provide means for holding small projectiles such as BB shot so that the shot may be discharged or projected with a rubber band. With this thought in mind this invention contemplates a pair of holding jaws pivotally mounted on a slider carried by a toy rifle or pistol and wherein the jaws are opened by a trigger to release the band and projectile.

The object of this invention is, therefore, to provide means whereby a small projectile such as a BB shot may be temporarily held in a rubber band on a gun stock whereby the shot and rubber band may be released by a trigger for discharging the shot.

Another object of the invention is to provide a sling shot toy gun that may be formed to provide either a rifle or a pistol.

A further object of the invention is to provide an improved sling shot which is of a simple and economical construction.

With these and other objects and advantages in view the invention embodies a stock having a breech with a barrel extended therefrom with a manually actuated breech block having jaws pivotally mounted thereon positioned in the breech and adapted to be actuated by a trigger operated sear for releasing the jaws to release a rubber band with a shot therein in which the ends of the rubber band are secured to the outer end of the barrel.

Other features and advantages of the invention will appear from the following description taken in connection with the drawings wherein:

Figure 1 is a side elevational view showing the toy gun with parts broken away and shown in section.

Figure 2 is a plan view of the gun with the parts in the position as shown in Figure 1.

Figure 3 is a view similar to that shown in Figure 1 showing the breech block drawn to the firing position and also showing a rubber band held between jaws of the breech block and stretched ready for firing.

Figure 4 is a cross section through the firearm taken on line 4—4 of Figure 3.

Figure 5 is a detail showing a sectional plan taken on line 5—5 of Figure 3 and illustrating a latch for holding the breech block in the firing position.

2

Figure 6 is a cross section through the outer end of the breech taken on line 6—6 of Figure 3.

Figure 7 is a cross section taken on line 7—7 of Figure 3 showing the rubber attaching brackets on the outer end of the barrel.

Figure 8 is a cross section through the breech and breech block of the gun taken on line 8—8 of Figure 2.

Referring now to the drawings wherein like reference characters denote corresponding parts the improved toy gun of this invention includes a breech 10 having a stock 11 at one end with the barrel 12 extended from the opposite end, a breech block 13 slidably mounted in a slot 14 in the breech and having gripping jaws 15 and 16 pivotally mounted thereon and a knob 17 extended from one side, and rubber bands 18 and 19 extended from arms 20 and 21 of a bracket carried by the outer end of the barrel 12 and connected, at their opposite ends to a sling 22.

The parts 20 and 21 of the rubber band mounting bracket are carried on the outer ends of arms 23 and 24 which extend from an eye 25 that is secured in an annular groove 26 which is spaced from the outer end of the barrel 12 of the gun. The parts 20 and 21 are held in position by braces 27 and 28, the ends of which extend into openings 29 and 30, respectively, in the sides of the gun barrel.

The sling 22 in the elastic bands 18 and 19 is positioned to extend into an opening 31 between the outer ends 32 and 33 of the jaws 15 and 16 and with the jaws clamped in the position shown in Figure 2 by an arm 34 a shot placed in the sling 22 is positioned in the opening 31 to prevent the sling sliding outwardly through the ends 32 and 33 until the jaws are released.

The jaws 15 and 16 are pivotally mounted on the breech block 13 by pins 35 and 36, respectively and the pins, which extend downwardly through the breech block 13, as shown in Figure 8, are secured together by a link 37 that is positioned on the outer surfaces of the jaws. Outward movement of the long ends of the jaws is limited by pins 38 and 39 that are positioned to extend into notches 40 and 41, respectively in the outer surfaces of the jaws.

The arm 34 is pivotally mounted on a pin 42 in the breech block and a lever 43 extending from the arm is positioned in a recess 44 in the under surface of the block 13, as shown in Figure 1.

With the parts arranged in this manner the breech block 13 is drawn rearwardly by the knob 17 that is mounted on the outer end of an arm 45 which extends through a slot that extends through one side of the breech, and as the breech block arrives at the firing position, as shown in Figure 3, a latch 46 positioned in a slot 47 in one side of the stock 10 and that is pivotally mounted on a pin 48, is moved inwardly to the position

shown in Figure 5 to retain the breech block 13 in the firing position as shown in Figure 3.

With the breech block in the position as shown in Figure 3 the trigger 49 pivotally mounted in an opening 50 on a pin 51 actuates a sear 52, that is pivotally mounted on a pin 53, and as the upper arm 54 of the sear is moved upwardly the arm 43 is moved upwardly whereby the arm 34 moves from the position between the ends of the jaws 15 and 16 whereby the jaws are released and the elastic bands eject the shot held in the sling 22 from the gun.

The breech block 13 is provided with grooves 55 and 56 into which tongues 57 and 58 on the inner surfaces of the sides of the breech 10, extend whereby the breech block is slidably mounted in the breech. The breech block may be provided with an extending tongue 59 that covers the slot 14 in which the block 13 is positioned, with the parts in the position shown in Figure 3, and that extends outwardly over the upper surface of the barrel 12 when the breech block is moved forwardly.

After releasing the jaws so that the shot or other device is projected the breech block is released by pressing on a button 60 on the outer end of the latch 46 whereby the inner end of the latch moves outwardly thereby releasing the breech block.

A guard 61 is provided for covering or protecting the trigger 49, and the breech 10 may be provided with a side plate 62 that is secured in position by screws 63. The latch 46 is positioned in the side plate 62 and the end of the latch may be provided with a projection 64 to limit inward movement thereof.

With the parts arranged in this manner BB shot, or other types of projectiles may be positioned in the sling 22 and held as shown in Figure 2 whereby with the breech block withdrawn to the position shown in Figure 3 the sling with the projectile therein may be released by the trigger.

It will be understood that modifications may be made in the design and arrangement of the parts without departing from the spirit of the invention.

What is claimed is:

1. A sling shot gun comprising a stock having a handle on one end with a barrel extended from the opposite end, means mounting an elastic band on the end of the barrel, a breech block slidably mounted in the stock, gripping jaws pivotally mounted on the breech block and positioned to retain a projectile held in the said elastic band, a sear mounted in the stock in the path of movement of said breech block, and a trigger for actuating the said sear to actuate the said jaws to release the projectile and elastic band.

2. A sling shot gun comprising a stock having a handle on one end with a barrel extended from the opposite end, means mounting an elastic band on the end of the barrel, a breech block slidably mounted in the stock, gripping jaws pivotally mounted on the breech block and positioned to retain a projectile held in the said elastic band, a latch positioned in the stock for retaining the breech block in a firing position, a lever pivotally mounted on the breech block in engagement with said jaws, a sear mounted in the stock in the path of travel of the breech block, and a trigger engaging said sear for actuating the lever to disengage the lever from the said jaws to release the projectile and elastic band.

3. A sling shot gun comprising a stock having a handle on one end with a barrel extended from

the opposite end, means mounting an elastic band on the end of the barrel, a breech block slidably mounted in the stock, gripping jaws pivotally mounted on the breech block and positioned to retain a projectile held in the said elastic band, a latch positioned in the stock for retaining the breech block in a firing position, a lever pivotally mounted on the breech block in engagement with said jaws, a sear mounted in the stock in the path of travel of the breech block, a knob extended from one side of the breech block by which the breech block is actuated by hand to stretch the elastic band for firing, and a trigger engaging said sear for actuating the lever to disengage the lever from the said jaws to release the projectile and elastic band.

4. In a sling shot gun, the combination which comprises a stock having a handle on one end and a barrel extended from the opposite end, said stock having a slot in the upper surface, a breech block slidably mounted in the slot in the upper surface of the stock, a latch pivotally mounted in the stock and positioned to retain the breech block in the firing position, jaws pivotally mounted on the breech block and having coacting outer ends positioned to retain an object in the recess therein, an arm pivotally mounted in the breech block and positioned to retain the said jaws in gripping relation, a trigger pivotally mounted in the stock, a sear also pivotally mounted in the stock and positioned to actuate the arm holding the jaws pivotally mounted on the breech block for releasing the jaws, said sear positioned to be actuated by the trigger, a bracket having extended arms mounted on the outer end of the barrel with an elastic band secured to the ends of the bracket on the end of the barrel and positioned to extend around an object positioned between the said gripping jaws.

5. In a sling shot gun, the combination which comprises a stock having a handle on one end and a barrel extended from the opposite end, said stock having a slot in the upper surface, a breech block slidably mounted in the slot in the upper surface of the stock, a latch pivotally mounted in the stock and positioned to retain the breech block in the firing position, jaws pivotally mounted on the breech block and having coacting outer ends positioned to retain an object in recesses therein, an arm pivotally mounted in the breech block and positioned to retain the said jaws in gripping relation, a trigger pivotally mounted in the stock, a sear also pivotally mounted in the stock and positioned to actuate the arm holding the jaws pivotally mounted on the breech block for releasing the jaws, said sear positioned to be actuated by the trigger, a sling, elastic bands connecting the sling to the ends of arms on brackets on the end of the barrel, and a knob extended from one side of the breech block for manually withdrawing the breech block to stretch the elastic bands.

JAMES R. KEADLE.
